UNITED STATES PATENT OFFICE.

ALBERT BUTZER, OF CARLYLE, ILLINOIS.

ENVELOP.

SPECIFICATION forming part of Letters Patent No. 598,359, dated February 1, 1898.

Application filed June 23, 1897. Serial No. 641,860. (No model.)

To all whom it may concern:

Be it known that I, ALBERT BUTZER, of Carlyle, in the county of Clinton and State of Illinois, have invented a new and useful Improvement in Mailing-Envelops, of which the following is a full, clear, and exact description.

The object of my invention is to provide a safety mailing-envelop of exceedingly simple, durable, and economic construction and capable of being readily manipulated and which after having been once closed cannot be opened without mutilation and detection.

A further object of the invention is to so construct the envelop that without an excess of material being used the end portions of the envelop, which are usually the weakest portions, may be rendered much stronger than under the ordinary construction of envelops without detracting from the appearance of the envelop or rendering the same in any manner bulky.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of the blank from which the envelop is made. Fig. 2 is a rear elevation of the envelop folded with the sealing-flap raised. Fig. 3 is a rear elevation of the envelop with the sealing-flap closed. Fig. 4 is a horizontal section on the line 4-4 of Fig. 2. Fig. 5 is an inner face view of the keeper-strip, illustrating the manner in which the locking-tongue engages therewith to prevent the sealing-flap from being raised without detection after it has once been closed. Fig. 6 is a transverse section through the envelop, taken on the line 6-6 of Fig. 2. Fig. 7 is a section similar to Fig. 6, taken on a larger scale and illustrating the relation of the locking-tongue to the keeper-strip after the envelop has been sealed. Fig. 8 is an outer face view of a portion of the locking tongue or strip; and Fig. 9 is a horizontal section taken through one end of the envelop, substantially on the line 9-9 of Fig. 3.

The blank from which the envelop is made consists of a front section or portion A, a back

section or portion B, and a sealing-flap C. The front section and the back section are of substantially the same length, being represented 55 as separated by the score-line 10, while a similar line 10^a indicates the separation between the front section and the sealing-flap of the blank. A wing 11 is formed at each end of the front section A of the blank, represented 60 as separated therefrom by score-lines 11^a, while narrower wings 12 are formed at the ends of the back section B, shown as separated therefrom by score-lines 12^a.

About centrally between the ends of the 65 back section B of the blank a keeper-strip D, constituting an extension from the outer edge of the said section, is located, which outer edge is the upper edge of the back of the envelop when made up. The keeper-strip is 70 of such length that when folded upon the inner face of the back section B it will extend practically to the bottom edge thereof, or where the back section connects with the front section. A series of longitudinal openings 75 13 is made in the keeper-strip, the material being only partially removed from the openings, the outer opening excepted, and the said material is bent inward and downward, as shown in Figs. 5, 6, and 7, forming a series 80 of flaps 14, each flap being provided with a slot or an opening 14^a where it is joined to the strip, the openings 14^a being about centrally between the side edges of the flaps.

A locking tongue or strip E is projected 85 from the central portion of the outer or sealing edge of the sealing-flap C. This tongue is provided with a series of cuts, so shaped as to form in the said tongue a series of pointed tabs 16, the cuts being indicated at 15, and 90 the construction of the locking-tongue is best shown in Figs. 1 and 8. Each tab 16 is provided with gum or a like material (preferably something insoluble when dry) spread over its inner face, whereby as the gum or other applied material dries the tabs will incline 95 inward at more or less of an angle to the body of the tongue, as shown in Fig. 8, in which the shaded lines indicate the extent to which the tabs incline from the body. The coated 100 surfaces of the tabs are indicated by the reference-numeral 16^a and are shown best in Figs. 1 and 2. The locking-tongue at its base is separated at its sides to a greater or less

extent from the sealing-flap by means of cuts 17, and a line of slight perforations, or a score-line 18, defines the inner end of the tongue, rendering the tongue readily separable from the sealing-flap.

The sealing-flap is provided upon its inner face, at its front edge, with the usual coating 19 of mucilage, and mucilage is likewise applied to what in the blank are the outer faces 10 of the wings 12, carried by the back section of the blank, and what are actually the inner faces of the wings 11, carried by the front section of the blank, are covered by a coating 20 of some kind of insoluble cement or of bi-chromated glue, which after having been once exposed to strong light can never be steamed open or softened, always remaining hard.

In completing the envelop the wings 12 are bent inward on the score-lines 12^a and their 20 gummed surfaces brought in engagement with and secured to the inner face of the front section A when the front and back sections are folded one upon the other. Next the wings 11 of the front section of the envelop 25 are carried over upon the outer face of the back section and attached thereto by the glue with which the said wings are covered. It will thus be observed that there is a double thickness at each end of the envelop, 30 (clearly shown in Fig. 9,) rendering the ends of the envelop, which are usually considered the weakest points, reinforced and strengthened to a great extent, and this improvement is effected without adding to the labor in forming the envelop and without adding to the 35 amount of material ordinarily used.

Before folding the back section upon the front section the keeper-strip, which is provided with a coating of glue 21 along its side 40 edges, is bent over upon the inner face of the back section and secured thereto, forming a pocket d, (shown in Figs. 6 and 7,) the flaps 14 extending within the interior of the completed envelop. A slot 22 is also made in the 45 back section B of the envelop near the point where the keeper-strip connects with said section. The flaps 14 in the keeper-strip are so produced that said flaps will be a trifle lower than the corresponding tabs on the 50 locking-tongue E, which is to enter the openings in said flaps, so that the tongue will have to be carried downward beyond the openings which the tabs of the tongue are to enter, the tabs of the said tongue entering the said openings only when the sealing-flap is in its 55 normal position when the envelop is closed.

In operation the envelop having been made up and the contents of the envelop having been placed in position the sealing-flap is carried 60 over the back of the envelop in the ordinary manner and the locking-tongue is passed within the envelop within the slot 22 into the pocket d, and the sealing-flap is carried downward beyond its score-line, so as to 65 bring the tabs of the back below the flaps of the sealing-strip, whereby upon straightening the sealing-strip or restoring it to the

ordinary closed position the pointed tabs of the locking-tongue will have been drawn up through the openings in the flaps of the keeper-strip, as shown in Fig. 5, thereby securely locking the tongue to the said strip, as shown in Fig. 7. Under this construction of the envelop no matter to what extent the envelop can be steamed it cannot be thus opened, 75 and if opened by a knife or other sharp instrument the fact will be detected, and in the event the sealing-flap is tampered with to such an extent that it may possibly become disengaged from the body it will be impossible to open said sealing-flap, since the locking-tongue E will have such close engagement with the body of the envelop as to cause the tongue to become separated from the sealing-flap before the latter can be opened. 85

Having thus described my invention, I claim as new and desire to secure by Letters Patent—

1. In a mailing-envelop or like receptacle, a blank provided at one edge with a keeper-strip projecting therefrom, and at the opposite edge with a locking-tongue arranged for locking engagement with the keeper-strip, the blank being provided with cuts in line with the sides of the tongue and extending into the 95 blank, the inner end of the tongue having a delicate connection with the blank, substantially as set forth.

2. In a mailing-envelop or like receptacle, a blank consisting of a front section, a back section and a flap-section, a keeper-strip projecting from the edge of the back section and formed with apertured flaps, the said back section being provided with a slot near the point where the keeper-strip connects therewith, and a locking-tongue projected from the sealing-flap of the envelop and provided with tabs adapted to enter the openings in the flaps of the keeper-strip, the said sealing-flap being provided with cuts at the sides of the locking-tongue extending into the body of the sealing-flap, substantially as shown and described. 105 110

3. In an envelop or like receptacle, a blank provided with an extension from one of its edges forming a keeper-strip, the said extension having openings made therein and apertured flaps extending from the wall of said openings, the said blank being also provided with a locking-tongue extending from the edge opposite that at which the keeper-strip 115 is located, the locking-tongue being provided with tabs adapted to enter the openings in the flaps of the keeper-strip, the said locking-tongue at its base being separated at the sides from the body of the blank by cuts extending 120 into the blank, the inner end of the tongue being defined by a score-line, whereby the tongue is readily separable from the blank, as and for the purpose set forth. 125

4. In an envelop or like receptacle, a blank 130 consisting of a front section, a back section and a flap-section, wings at the ends of the front and back sections, the wings of the front section being arranged to be carried over the

wings of the back section and to engage with said back section, a keeper-strip projecting from the back section and having a series of apertured flaps formed therein, the keeper-strip having cementing surfaces at its sides for engagement with the inner face of the back section of the completed envelop, to form a pocket, the back section being provided with a slot near the point where the keeper-strip connects with said back section, the said slot leading into said pocket and a locking-tongue projecting from the flap-section of the envelop or receptacle and provided with tabs arranged to enter the openings in the flaps of the keeper-strip, the said locking-tongue at its base being separated at the sides by cuts from the sealing-flap, the inner ends of the cuts being united by a score-line defining the inner end of the tongue, as and for the purpose specified.

5. An envelop or like receptacle provided with a back section having a slot therein near its edge and a pocket formed upon the inner face of the back section and communicating with said slot, the inner wall of said pocket being provided with flaps projecting into the interior of the envelop, each flap being formed with an aperture at its junction with the inner wall of the pocket, and a locking-tongue projecting from the sealing-flap of the envelop, said tongue being adapted to enter the said pocket through the slot in the back section, the said tongue being provided with tabs projecting beyond the plane of its inner face and adapted to enter the openings in the flaps of the said pocket, substantially as described.

6. An envelop or like receptacle having a pocket formed upon the inner face of the back section, the back section being formed with a slot opening into the said pocket, the pocket

being provided with projections extending 40 within the interior of the envelop and each projection being provided with a slot or opening, and a locking-strip projected from the sealing-flap of the envelop and arranged to enter the flap in the back section and extend 45 into the said pocket, the said locking-strip being provided with inclined tabs constructed to enter the openings in the projections from the pocket, for the purpose specified.

7. An envelop or like receptacle having a 50 pocket formed upon the inner face of its back section, the said back section being formed with a slot opening into the said pocket, the inner wall of said pocket being provided with projections extending within the interior of 55 the envelop, and each provided with an aperture at the junction of the projection with the inner wall of the pocket, and a locking-strip projected from the sealing-flap of the envelop and arranged to enter the slot in the back section 60 and extend into the said pocket, the said locking tongue or strip being provided with tabs adapted to enter the apertures in the projections from the pocket, the said sealing-flap being provided with cuts at the sides of the 65 tongue extending into the body of the sealing-flap, the inner end of the tongue having a delicate connection with the sealing-flap, whereby the tongue is readily separable therefrom, the said pocket being formed by a strip 70 forming an extension of the back section and folded upon and secured to the inner face of the said back section, substantially as set forth.
